(No Model.)

T. O'BRIEN.

TRICYCLE.

No. 394,287.

Patented Dec. 11, 1888.

UNITED STATES PATENT OFFICE.

THOMAS O'BRIEN, OF NEW YORK, N. Y.

TRICYCLE.

SPECIFICATION forming part of Letters Patent No. 394,287, dated December 11, 1888.

Application filed March 8, 1888. Serial No. 266,532. (No model.)

To all whom it may concern:

Be it known that I, THOMAS O'BRIEN, of the city, county, and State of New York, have invented an Improvement in Tricycles, of which 5 the following is a specification.

In my improved tricycle the tubular frame at its forward portion is made in two separable parts, wherein one tube passes within the other to form a joint upon which the steering- 10 wheel can be swung around toward or between the main wheels to render the machine compact for transportation or storage, and when swung out of place the parts of the frame are rendered rigid by a clamping mechanism. The steering-wheel fork is connected 15 with a spring-plate that also forms a mud-guard, and the rod of the handle-bar is attached to this spring, so that but little of the vibration of the steering-wheel is transmitted 20 to the handle-bar.

In the drawings, Figure 1 is an elevation of my improved tricycle, the left-hand driving-wheel being removed. Fig. 2 is a plan of the same, and Fig. 3 is a vertical section through 25 the forward part of the spine.

The driving-wheels A, their axle A', and the steering-wheel B, and the bearings of all these wheels, are of the usual character, and the driving mechanism, consisting of the sprocket- 30 wheels a a', chain b, the depending links c c', and connecting-rods d d' and foot-piece e e', is similar to those heretofore described by me in my Patents Nos. 372,428 and 372,429, and my pending application, Serial No. 253,172, 35 allowed January 10, 1888. The pedals e' e' are connected by their cranks to the axle of the sprocket-wheel a, and the ends of the connecting-rods d d' are connected to the pedal-shafts.

The frame of the tricycle is composed of a longitudinal and horizontal portion or spine, 1, the vertical back portion, 2, vertical forward portion, 3, the vertical central portion, 4, and horizontal portion or bar 5, all of which 45 are rigidly brazed together. The axle of the main driving-wheels is supported at its several bearings by a central fork, f, connected upon the bar 5, and by the bridge g, connected upon the upright portion 2. There are adjustable seat-rods h h', which are received 50 within the vertical portions 4 and 2 of the

frame, and these rods h h' are adapted to carry any well-known form of seat or saddle.

At the forward portion of the saddle-rod h is a T-head, to which are pivoted the upper 55 ends of the adjustable links c c'. Upon the forward end of the saddle-rod h' is another T-head. This latter T-head is vertical, and through it passes the vertical rod 6 of the rear handle-bars, 7, and there is an arm, 8, 60 connected to the lower end of the rod 6, and this arm 8 extends out below and in line with the handle-bar 7, and to its outer end is connected the controlling-rod 9, which extends to and is connected with the front handle-bars, 65 10. The saddle-rods h h' are adjustable vertically in the usual manner by split collars.

The vertical portion 3 of the spine is adapted to receive within it the tube i, which tube is formed with the neck i', which in turn is connected with the inclined front tube, k. A small vertical tube, 12, is brazed upon the base of the vertical portion 3 at the curve where it joins with the horizontal portion 1, and there is a screw-threaded rod, 13, which 70 is pinned in a head, 14, which head is brazed rigidly into the base of the tube i, and upon the end of this rod 13 are the clamping-nuts 75 15. There is a collar, 16, surrounding the tube i above the tube 3, and there are lugs 80 17 upon the sides of this collar, which lugs are adapted to be received in notches formed in the top of the tube 3. Figs. 1 and 3 illustrate these parts of the machine connected together rigidly, wherein the clamping-nuts 15 85 keep the lugs 17 in place in the notches at the top of the tube 3 and prevent the tube i turning within the tube 3.

If it is desired to fold the machine for transportation, the nuts 15 are loosened and the 90 tube i is raised so that the lugs 17 come above the upper edge of the tube 3, in which position the tube i can be turned to bring the forward part of the machine around and within the width of the driving-wheels, so as to compact the machine together for crating and 95 transportation, or for storage.

It is to be understood that this construction does not weaken the parts or interfere with the efficiency of the machine. The front 100 forks, l, are connected to the bearings of the steering-wheel, and to the upper bridge of said

forks is rigidly secured a spring-plate, *m*, whose contour conforms to the periphery of the steering-wheel. Connected to the forks and to the lower part of this plate *m* are bars 5 *n*, which bars are preferably springs projecting from the fork and hinged at their outer ends to the plate *m*. There is a tubular step, *o*, brazed and riveted upon the exterior of the plate *m*, the short tubular portion of which 10 agrees in diameter with the tube *k*, and there is a tube, *o'*, which is rigidly secured at its lower end to the tubular portion of the step *o* and passes through the tube *k*, and the upper end of this tube *o'* is split and provided with 15 a split collar for clamping the rod *r* of the handle-bars 10, which rod *r* passes into the tube *k*.

It will be evident from this construction that when the handle-bar 10 is turned it will 20 also turn the tube *o'*, step *o*, plate *m*, forks *l*, and steering-wheel *b*, and thus the machine will be guided and controlled. The plate *m*, while carrying the weight of the forward part 25 of the machine, also forms a spring-plate that yields to inequalities of road-surface and lessens vibration and adds to the ease and comfort of those riding the machine. The weight upon the spring *m*, when in use, tends to straighten or flatten the same and to bend the 30 arms *n* in so doing. This plate *m* and a downward extension, *m'*, which is added to it, form an effective mud-guard to the wheel *B*.

Any desirable or well-known form of brake mechanism may be employed in connection 35 with my improved tricycle, either to the main-wheel axle or to the steering-wheel, and I have therefore not shown any brake mechanism upon the drawings, because the adaptation of any well-known form to my improved 40 machine is merely the exercise of mechanical skill.

The construction herein shown and described whereby I am enabled to swing the

steering-wheel around toward or between the main wheel or wheels is equally applicable 45 for use in a velocipede or bicycle of the safety pattern.

I claim as my invention—

1. The combination, in a tricycle, with the driving and steering wheels and the forward 50 handle-bar, of the front forks, *l*, the spring-plate *m*, side spring-bars, *n*, the step *o*, tubes *k* and *o'*, and steering-rod *r*, substantially as set forth.

2. The combination, in a tricycle, with the 55 driving and steering wheels and the handle bar and rod, of the fork *l*, side bars, *n*, a curved spring-plate, *m*, and a tubular connection between the rod of the handle-bar and the top of the spring-plate *m* to the rear of the forks, 60 whereby the spring-plate yields to the weight that is carried by it, substantially as set forth.

3. In a tricycle, the combination, with the spine having a longitudinal portion, 1, and vertical portion 3, and the tube 12, of the neck 65 *i'*, the inner tube, *i*, connected with the neck *i'*, the threaded rod 13, fastened to the tube *i*, the clamping-nuts 15, and lugs 17, substantially as specified.

4. In a tricycle or other velocipede, the combination, with the neck and a longitudinal spine connecting the front and rear wheels, of a vertical outer tube, 3, formed with the spine, a vertical inner tube, *i*, formed with the neck and received within the tube 3, lugs 75 or a similar device for preventing the tubes turning upon one another, and mechanism, substantially as specified, for locking the parts, substantially as set forth.

Signed by me this 5th day of March, A. D. 80 1888.

THOMAS O'BRIEN.
